METHOD FOR MAKING POINTS FOR THE
ENDS OF RODS AND THE LIKEAdolf W. Keuffel, Montclair, N. J., assignor to
Keuffel & Esser Company, Hoboken, N. J., a
corporation of New Jersey

Application May 23, 1934, Serial No. 727,051

6 Claims. (Cl. 29—143.2)

This invention relates to a method for making points for the ends of rods such as surveyor's ranging poles and the like, Jacob's staffs, the legs of tripods and similar articles requiring sharp and hard points.

Heretofore, points for ranging poles, for instance, have been made by forming a steel tube portion at the lower end of the pole into a tapering shape which is thus hardened.

The present invention seeks to provide a sharp end for articles of the character described in which a thinner walled tubular portion may be used without sacrifice of strength; in which the point may be readily formed and is capable of being hardened by a simple swaging operation forming the point to the desired shape and which permits the use of a point of a harder material, when desired.

Another object of the invention is to provide an all steel pole which shall be no heavier than a wooden pole. Accordingly, a tubular pole is provided which is corrugated whereby a thinner walled tube may be used having the requisite strength.

It is also an object of the invention to provide for the effective securing of the point with the tubular portion at the lower end of the pole. To this end, the tubular end of a point member or shoe is telescoped within the tubular portion and the overlapping parts are then shaped to a taper and are thereby interlocked against separation.

These and other objects of the invention and the means for their attainment will be more apparent from the following detailed description, taken in connection with the accompanying drawing illustrating one embodiment by which the invention may be realized and in which:

Figure 1 is a view, in longitudinal section, showing the shoe and tube assembled, before swaging operation forming the point therefrom;

Figure 2 is a view, also in longitudinal section, showing the completed point applied to a tubular steel shaft;

Figure 3 is a view, in longitudinal section, showing a modification of the invention applied to a wooden pole;

Figure 4 is a transverse sectional view taken in the plane indicated by the line 4—4 of Figure 3, looking in the direction of the arrows; and

Figure 5 is a transverse sectional view taken in the plane indicated by the line 5—5 of Figure 2.

What may be called the blank from which the shoe is formed into its final shape (Figure 2) is illustrated generally at 8, in Figure 1. It is preferably of cold rolled or high carbon steel turned

into a cylindrical portion 9 with a frusto conical end 10. The opposite end 11 is of reduced diameter to form a shoulder 12, which is relieved on the inside as a tubular bore 13. A sleeve or tube 14 of a softer steel receives the end 11 of the shoe 8 and extends to shoulder 12. For convenience in handling, particularly during manufacture, the tube is secured to the shoe, as by spot welding at a few points although, obviously, the parts may be assembled with a drive fit or, if necessary, can be held together with a rivet or two.

The point is then formed and assumes the shape illustrated in Figures 2 and 3 preferably by a swaging operation in which the shoe will adjust itself by reason of the hollow bore 13 and will be elongated into the desired tapered point when subjected to the hammer blows of the swaging machine. The tapering shape commences preferably a short distance below the upper end 19 of the tubular shoe part 11 so that the upper end 19 of the tubular shoe part 11 is cylindrical within the telescoping tubular portion 14 and an even stronger section is afforded at the part where the taper begins than where the shoe part 11 terminates exactly at the beginning of the taper, as shown in Figure 3. Since the tubular shoe portion 11 flares outwardly in an upwardly direction with the end of the tubular portion 14 or 17 constricted thereabout, the two parts are interlocked and separation prevented. The swaging operation effectively shapes the telescoping parts to tapering form even when a corrugated tube is used.

By this method of manufacture, a very superior hard point may be made by using a high carbon steel for the shoe piece which, after being assembled with the tube and placed in the heating oven, will become hardened, as is the characteristic of high carbon steel when it is cooling down, and this will be accomplished at the same time that the point is being swaged.

A short tubular portion 14 (Figure 3) may receive the end of a wooden leg or pole 16 as shown in Figure 3, or it may be one end of a steel tube serving as the pole, in which event, if desired, it may be corrugated for strength, as shown at 17 (Figure 2) whereby a thinner walled tube can be used.

Thus a hard steel point is provided which can be shaped so as to give the least possible resistance to entry into the ground. It is adaptable for round poles, corrugated poles, for shoes only of wooden rods, such as ranging poles, for shoes

of tripods, Jacob's staffs and similar articles requiring sharp and hard points.

Various modifications will occur to those skilled in the art in the composition, configuration and disposition of the component elements going to make up the invention as a whole as well as the use to which the point is put and no limitation is intended by the phraseology of the foregoing description or illustrations in the accompanying drawing, except as indicated in the appended claims.

What is claimed is:—

1. The method of making a hard point for poles comprising forming a shoe part of steel having a tapering end and the opposite end of reduced constant diameter, inserting the end of reduced diameter in a tube portion of constant diameter and forming the parts to tapering shape.
2. The method of making a hard point for poles comprising forming a shoe part of steel having a tapering end and the opposite end cylindrical and of reduced diameter and provided with a hollow bore, inserting said portion of reduced diameter in a cylindrical tube portion and forming the parts to tapering shape.

3. The method of making a hard point for poles comprising forming a solid pointed shoe part of high carbon steel having a tubular portion remote from the point, inserting the tubular portion thereof in a tube of low carbon steel and swaging the parts to a shape tapering toward the point. 5

4. The method of securing together portions of a point for poles comprising forming a point portion with an outwardly flaring end and constricting the end of a tubular portion thereabout. 10

5. The method of making a hard point for poles comprising forming a shoe part with a cylindrical portion, inserting the cylindrical portion in a tube portion and thereafter forming the shoe part 15 and the tube portion in contact therewith to tapering shape.

6. The method of securing together portions of a point for poles comprising forming a point portion with an outwardly flaring end, the diameter of which, proximate the point portion, is less than the diameter of the adjacent portion to define a shoulder therebetween and constricting thereabout the end of a tubular portion abutting the shoulder. 20 25
